UNITED STATES PATENT OFFICE.

KENNETH HOWIE, OF NORRISTOWN, PENNSYLVANIA, ASSIGNOR TO WILDMAN MFG. CO., OF NORRISTOWN, PENNSYLVANIA, A CORPORATION OF PENNSYLVANIA.

TAKE-UP MECHANISM FOR KNITTING MACHINES.

Application filed May 20, 1921. Serial No. 471,091.

To all whom it may concern:

Be it known that I, KENNETH Howie, a citizen of the United States, and resident of Norristown, in the county of Montgomery and State of Pennsylvania, have invented certain new and useful Improvements in Take-Up Mechanism for Knitting Machines, of which the following is a specification.

One object of my invention is to provide a take-up mechanism for knitting machines in which the driving of the take-up rolls will occur through a positive clutch device, as distinguished from a friction clutch using such frictionally engaging members as fibre discs.

I aim to provide a positive clutch having metal to metal engaging surfaces, but which will be free from the objection existing to certain prior forms, in that, in my improvement the clutch members are not gradually engaged and disengaged but are either all the way in engagement with each other or all the way out of engagement.

This avoids the successive knocking actions and the tendency of the clutch points to chip off or wear away or assume a rounded form instead of remaining square edged, and working with the greatest efficiency.

Other features of the invention will be clear from the following description and accompanying drawings, in which—

Figure 1 is a side view of a take-up mechanism with the clutch members out of driving relation, the take-up rolls being at rest.

Fig. 2 is a view similar to Fig. 1 with the housing or supporting frame of the take-up rolls tilted downwardly due to the length of the fabric knit off from the machine, the clutch members now being in engagement to drive the take-up rolls.

Fig. 3 is a view similar to Fig. 2, but with the housing or frame of the take-up rolls tilted upwardly, due to the take-up rolls climbing on the fabric, and the clutch about to be thrown out of operation to stop the take-up action of the rolls.

Fig. 4 is a plan view partly in section of a portion of a take-up mechanism embodying the invention.

Fig. 5 is a view looking from the front of

the take-up mechanism and a part of the frame.

In these drawings 1 is the main frame of the take-up mechanism; 2 is a housing or frame in which take-up rolls 3 are journaled.

This frame has a shaft 19 bearing in the main frame and this take-up housing 2 is adapted to swing, with the axis of this shaft as a center. The take-up rolls are geared to rotate in unison.

One of the take-up rolls has a worm wheel 5 connected therewith. A worm 4' meshes with the worm wheel. This worm has a clutch member 4 having a tooth or teeth on its upper face adapted to be engaged by a clutch member 6, which is splined at 6' to the vertical shaft 18. This shaft is driven, as in ordinary practice, by a gear on its lower end engaging a rack fixed to a part of the machine frame. The worm 4' is loose on this shaft. The upper end of the shaft bears in a suitable arm 7.

The sliding clutch member 6 is in the form of a sleeve, and it is provided at its upper part with a flange 6^a having a cut-away under part providing a cam incline 6''. It also has a second flange 6^b spaced apart from the flange 6^a, providing an annular groove between them to receive, at times, a spring pin or plunger 10, carried by a box 2' on the take-up frame 2. This box also carries a spring pin or plunger 11 which is to cooperate with the cam incline 6'' in releasing the clutch.

Each of the pins 10 and 11 has its own spring 12 or 13 forcing the pin (which is rectangular in cross section) out to the right of the boxing 2'. The movement of these plungers is limited by stop pins 14, 15 respectively.

Supposing the clutch to be out of action, as in Fig 1, at which time the slideable member 6 is held up, so that its tooth 6^x will be above the horizontal plane of and consequently not in engagement with the tooth of the worm 4. This clutch member 6, however, will be in constant rotation, because it rotates with the shaft 18.

As the fabric is knit off and consequently lengthens, the take-up rolls weighing thereon will move down and tilt the frame 2 into

the position of Fig. 2, thus withdrawing plunger 10 from engagement with clutch member 6, allowing this to drop all the way down and into full driving engagement with the clutch member 4 of the worm, whereupon the worm will be driven and through the worm wheel 5 the take-up rolls will be turned to take up the fabric as it is knit off from the needles.

10 This engagement of the clutch members is due to the full stroke action of the clutch sleeve 6, which when released by the dog or pin 10 is free to drop all the way down into engagement with the lower clutch member.

15 If now the take-up rolls climb on the fabric, due to the difference between their take-up capacity and the rate of production of knitting at the needles, the housing or frame 2 will be tipped to the position shown in Fig. 3, and when the cut-away part at the under side of the flange 6^x comes around opposite the pin 11, this will spring into the space and the incline 6^y will ride on the pin and thus the whole clutch member 6 will be lifted, so that its tooth 6^x will be withdrawn from the tooth of the worm and the worm will cease to drive the take-up rolls. The lifting of the clutch member 6 will 20 bring its annular groove opposite the spring pin 10, so that this will immediately spring into place and hold the clutch member 6 lifted.

25 This relation of the parts will continue for only a short time, because the fabric, as it continues to be knit off, will increase in length and allow the take-up rolls, which are gripping it, to lower, and the plunger 10 will soon be withdrawn from the clutch member 6. This will now fall and resume driving the worm. It will be seen from the above that the clutch member 6 is allowed to fully engage the worm clutch or it is withdrawn completely from engagement therewith. In other words, the clutch is either all the way in or all the way out. It does not operate by bringing its two members gradually into engagement. Such gradual action results in a succession of taps 40 or knocks as the engagement is initiated and this is objectionable not only because of the noise but undue wear takes place at the clutch points or pins, and the edges or corners of these points or teeth are liable to be chipped. My clutch may be said to be of full stroke character; that is to say, once the setting of the clutch for driving is initiated, the setting action is carried on to the fullest extent, and on the contrary, once 45 the release of the clutch is started, the complete release is the result.

50 In the foregoing description, and in the drawings, I have disclosed my invention in the form now best known to me, but it will 55 be understood that the invention may be em-

bodied in organizations other than that shown, and driven by means other than that illustrated. The foregoing specification, of which the drawing forms a part, is, therefore, to be regarded as descriptive of the invention and not as a limitation upon its scope, which is defined by the appended claims.

60 The underlying feature of the invention is a clutch, the members of which have a full throw relative movement into and out of engagement at each change of the clutch in consequence of variations in the rate of travel of the fabric between the take-up rolls.

65 I claim:

70 1. Take-up mechanism for knitting machines comprising fabric take-up means, driving means therefor including clutch members, means for imparting rotation to one of said members, power operated means for giving a relative movement to the clutch members from engaged to disengaged position for releasing them, said power operated means being rendered effective by the decrease in the rate of travel of the fabric for releasing the clutch, substantially as described.

75 2. Take-up mechanism for knitting machines comprising fabric take-up means, driving means therefor including clutch members, means for imparting rotation to one of said members, power operated means for giving a full throw relative movement to the clutch members from engaged to disengaged position for releasing them, said power operated means being rendered effective by the decrease in the rate of travel of the fabric for releasing the clutch, said clutch members having inter-engaging teeth 80 and when released having their teeth lying in different but parallel planes, substantially as described.

85 3. Take-up mechanism for knitting machines comprising fabric take-up means, driving means therefor including toothed clutch members, means for imparting rotation to one of said members, means for giving a relative movement to the toothed clutch members from engaged to disengaged position for releasing them, said means deriving its power from that of the machine, and being controlled to utilize said power by the decrease in the rate of travel of the fabric, substantially as described.

90 4. Take-up mechanism for knitting machines comprising a pair of take-up rolls, a movable support therefor, driving means for the take-up rolls including toothed clutch members, means for imparting rotation to one of said members, means for giving a full throw relative movement to the toothed clutch members from engaged to disengaged position for releasing them, said means deriving its power from that of the 95 machine.

machine, and being rendered effective in releasing the clutch by the pivotal movement of the support, due to the decrease in the rate of travel of the fabric, substantially as described.

5. In combination in a take-up for knitting machines, fabric take-up means, a pair of clutch members for driving the same, means for driving one of the said members, a cam connected with said member and rotating therewith, a pin for engaging the cam to cause the release of its connected clutch member by the power derived from the machine, and means for setting the pin in or out of engagement with the cam in accordance with variations in the rate of travel of the fabric between the machine and take-up means, substantially as described.

6. In combination in a take-up for knitting machines, fabric take-up means, a pair of clutch members for driving the same, means for driving one of the said members, a cam connected with said member and rotating therewith, a pin for engaging the cam to cause the release of its connected clutch member by the power derived from the machine, and means for setting the pin in or out of engagement with the cam in accordance with variations in the rate of travel of the fabric between the machine and take-up means, said pin being mounted to yield when being positioned into engagement with the cam, substantially as described.

7. In combination in a take-up for knitting machines, fabric take-up means, a pair of clutch members for driving the same, means for driving one of the said clutch members, a cam connected with said member and rotating therewith, a device for engaging the cam to cause the release of its connected clutch member by the power derived from the machine, means for setting the device in or out of engagement with the cam in accordance with variations in the rate of travel of the fabric between the machine and the take-up means, and means for holding the clutch members in separated position when released, said last mentioned means being set in and out of operation by the same means which sets the said device in and out of engagement with the cam, substantially as described.

8. In combination in a take-up for knitting machines, fabric take-up means, a pair of clutch members for driving the same, means for driving one of the said clutch members, a cam connected with said member and rotating therewith, a pin for engaging the cam to cause the release of its connected clutch member by the power derived from the machine, means for setting the pin in or out of engagement with the cam in accordance with variations in the rate of travel of the fabric between the ma-

chine and the take-up means, a collar on the clutch member above the cam and spaced apart therefrom, a pin for engaging the collar to hold the clutch members separated, said pin being set into and out of holding engagement with the collar by the same means which sets the first pin in and out of engagement with the cam, both of said pins being spring pressed to yield when they are advanced to operative position, substantially as described.

9. In combination in take-up mechanism for knitting machines, fabric take-up means, a pair of clutch members arranged coaxially one above the other and having inter-engaging teeth between them, a power transmitting connection between the lower clutch member and the take-up means, means for rotating the upper clutch member, means for giving a full throw upward movement to the upper clutch member to release the lower clutch member, to thereby stop driving the take-up means, said full throw means deriving its power from that of the machine, and being controlled to utilize said power by the decrease in the rate of travel of the fabric, and going out of action when the rate of travel of the fabric increases, the upper clutch member then resuming engagement with the lower clutch member by a full throw movement, to drive the take-up means, substantially as described.

10. In combination in take-up mechanism for knitting machines, fabric take-up means, a rotating shaft, a pair of clutch members on said shaft, one of which is splined thereto and the other loose thereon, power transmitting means between the loose clutch member and the take-up means, a cam connected to the splined clutch member and driven by the power of the machine through said rotating shaft, a member cooperating with the cam and set into engagement therewith as a result of the decrease in the rate of travel of the fabric, to retract the splined clutch member by a full throw movement out of engagement with the loose clutch member, substantially as described.

11. In combination in take-up mechanism for knitting machines, fabric take-up means, a rotating shaft, a pair of clutch members on said shaft, one of which is splined thereto and the other loose thereon, power transmitting means between the loose clutch member and the take-up means, a cam connected to the splined clutch member and driven by the power of the machine through said rotating shaft, a member cooperating with the cam and set into engagement therewith as a result of the decrease in the rate of travel of the fabric, to retract the splined clutch member by a full throw movement out of engagement with the loose clutch member, said rotating shaft being arranged substantially vertical with the splined clutch member and

cam above the loose clutch member, said splined clutch member falling by gravity into engagement with the loose member by a full throw movement when released from its retracted position by the retirement of the said cooperating member due to the increased rate of travel of the fabric.

12. In combination in take-up mechanism for knitting machines, a pair of take-up rolls, a pivoted frame carrying said rolls, a vertical drive shaft, a worm loose thereon, a worm gear meshing with the worm and connected to one of the take-up rolls, a toothed clutch member fixed to the worm, a 10¹⁵ slideable toothed clutch member rotating with the shaft, a cam connected with the slideable clutch member and rotating therewith, a collar connected with the cam, a pair of spring pins, one for engaging the cam to retract the sliding clutch by the power derived from the machine and one for engaging the collar to hold the sliding clutch retracted, said pins being mounted on the pivoted frame to be 20²⁵ set in position for retracting and holding the sliding clutch when the rate of travel of the fabric decreases and to be withdrawn, for the re-engagement of the clutch members

when the rate of travel of the fabric increases again, said clutch members when disengaged having their teeth lying in different but parallel planes, substantially as described.

13. In combination in take-up mechanism for knitting machines, fabric take-up means, a rotating shaft, a pair of clutch members on 30³⁵ said shaft, one of which is splined thereto and the other loose thereon, power transmitting means between the loose clutch member and the take-up means, a cam connected to the splined clutch member and driven by the power of the machine through said rotating shaft, a member cooperating with the cam and set into engagement therewith as a result of the decrease in the rate of travel of the fabric, to retract the splined clutch member 40⁴⁵ by a full throw movement out of engagement with the loose clutch member, and a pivoted support for the take-up means having an arm extending upwardly alongside the said shaft and carrying the said member, substantially as described.

In testimony whereof, I affix my signature.

KENNETH HOWIE.
